D 17160

UNITED STATES PATENT OFFICE.

NICHOLAS RAPPLEYEA, OF ROCHESTER, NEW YORK, ASSIGNOR TO THE STEIN MANUFACTURING COMPANY, OF SAME PLACE.

DESIGN FOR A BURIAL-CASKET.

SPECIFICATION forming part of Design No. 17,760, dated October 4, 1887.

Application filed May 28, 1887. Serial No. 239,705. Term of patent 14 years.

To all whom it may concern:

Be it known that I, NICHOLAS RAPPLEYEA, of Rochester, in the county of Monroe, in the State of New York, have invented a new and original Design for Burial-Caskets, of which the following, taken in connection with the accompanying drawings, is a full, clear, and exact description.

My invention relates to a new and original design for burial-caskets; and it consists, essentially, of the design for the ornamental molding used on burial-caskets, as herein described and claimed.

In specifying my design reference is had to the accompanying drawings, forming part of this specification, in which like letters of reference indicate corresponding parts.

Figure 1 is a top plan view of my design applied to a burial-casket lid. Fig. 2 is a transverse section taken on line $x-x$, Fig. 1, showing the contour of the ornamental molding and the face-panel of the casket-lid, and Fig. 3 shows a modification in the contour of the face-panel of the lid, these three views being deemed essential to illustrate my design.

The leading feature of my design consists in an ornamental border-molding having a concave or hollow arch shape in cross-section, its margins terminating in reversed curves, with a narrow curved base-molding meeting the outer edge of the casket-lid on one side and curving gracefully to the face-panel on the other side, the said molding extending marginally around or in proximity to the outer edge of the casket lid or top, thus securing a novel and pleasing effect and greatly beautifying the appearance of the casket-lid.

A denotes the casket lid or top, which may be of any desirable form or material.

4c a is the ornamental molding applied to the casket-lid, as best shown in the top plan view, Fig. 1.

b is the face-panel.

c denotes the curve of the inner margin of the molding to the face-panel, and d shows the 45 reverse curve on the outer margin of the molding a, and e is the curved outer edge of the molding a, forming the outer edge of the casket lid or top.

The molding a is of the contour best shown 50 in the transverse section, Fig. 2, the top of the molding being concave like the interior curve of an arch, while the marginal edges are reversely curved, as best illustrated in the aforesaid sectional view, Fig. 2. The peculiarly-shaped concave top molding, with its ornamental edges extending marginally around the casket-lid, as stated before, presents a very pleasing appearance in connection with the panels of the top of the casket.

The face-panel b may be either curved in cross-section, as shown in Fig. 2, or flat, as shown in Fig. 3, its form or contour in cross-section being wholly immaterial.

As applied to the casket-lid or top A, the 65 ornamental molding is arranged around the exterior of the lid, as best shown in Fig. 1.

Having thus fully described my new design, what I claim as new, and desire to secure by Letters Patent, is—

A design for a burial-casket, the same consisting of the molding a, having the concaved top and curved marginal edges c d, surrounding the panels b, substantially as herein shown and described.

In testimony whereof I have hereunto signed my name, in the presence of two attesting witnesses, at Rochester, in the county of Monroe, in the State of New York, this 25th day of May, 1887.

NICHOLAS RAPPLEYEA.

Witnesses:

FRANK M. ELLERY,
GEO. P. HESS.
